Primary Examiner — Doris Clark(74) *Attorney, Agent, or Firm* — Dority & Manning, P.A.(57) **CLAIM**

The ornamental design for a grab rail with two knurled portions and cavity for light, as shown and described.

DESCRIPTION

FIG. 1 is a perspective view of the grab rail with two knurled portions and cavity for light according to the present design; FIG. 2 is an alternate perspective view of the grab rail with two knurled portions and cavity for light of FIG. 1; FIG. 3 is an end view of the grab rail with two knurled portions and cavity for light of FIG. 1; FIG. 4 is a right or left side view of the grab rail with two knurled portions and cavity for light of FIG. 1; FIG. 5 is a top view of the grab rail with two knurled portions and cavity for light of FIG. 1; FIG. 6 is a bottom view of the grab rail with two knurled portions and cavity for light of FIG. 1; and, FIG. 7 is a perspective view of the grab rail with two knurled portions and cavity for light of FIG. 1, as installed using stanchions. The claimed design comprises the elements shown in solid lines, the elements shown in dotted lines forming no part of the claimed design.
